G. SCHAULY
BY J. CO. MINERATE

UNITED STATES PATENT OFFICE

GEORGES SCHAULY, OF NANTES, FRANCE

MINER'S SAFETY LAMP INDICATING THE AMOUNT OF FIRE DAMP IN THE AIR

Application filed August 10, 1927, Serial No. 212,122, and in France August 16, 1926.

My invention is based upon the observation of a flame of a miner's safety lamp which is more or less elongated according as the amount of fire-damp in the surrounding air increases, and whose temperature increases accordingly.

I cause these two factors to act concurrently upon a suitable thermo-electric couple, variations in current are measured by a milli-ampere meter carrying a scale graduated in percentages of fire damp.

The invention is further adapted to produce distant signals when the amount of fire-damp becomes dangerous at a given point, and the variations in the thermo-electric current from the said couple are caused to act at a distance over a circuit containing a suitable signal device of an optical, magnetic, electric, acoustic or like nature.

The thermo-electric couple which offers the best results is composed of nickel and chromium.

The thermo-electric device may be placed above the lamp, but I prefer to dispose it in the interior of the lamp and above the flame; it may comprise a single element or a plurality of elements, connected in series or in parallel.

The thermo-electric device is herein disposed on the axis of the flame, and the hooked-shaped thermo-electric joint is directly exposed to the action of the flame, the remainder of the device as well as the conductors being covered with asbestos.

The conductors of the thermo-electric device are connected with a pair of insulated metallic rings placed upon the exterior of the lamp; however one ring may be replaced by the metal body of the lamp, or the said ring may be riveted to the lamp, and the latter may also be connected with one end of the thermo-electric device in order to reduce the temperature of the latter.

The connection between the end or ends of the thermo-electric device and the insulated ring or rings is assured by insulated conductors disposed in a transverse tube soldered to the metal body of the lamp, so as not to interfere with the functioning of

the lamp and the circulation of oil in the wick.

The appended drawings show by way of example a miner's safety lamp according to the invention.

Fig. 1 is an elevational view of the apparatus, partly in section.

Fig. 2 is a plan-section view.

Fig. 3 is a detail view showing the operation of the lamp.

As observed in the drawings, the safety lamp 1 of the Davy or other type is provided immediately above the flame 2, and in the axial position, with a hook shaped joint 3 of a nickel-chromium thermo-electric couple 4 whose rigid conducting supports 5-6 are covered with asbestos; said supports are mounted in the electric terminal pieces 8-9 which are insulated from the main body and are connected by the insulated conductors 10-11, passing through the tubes 12-13 soldered to the main body, with the conducting rings 14-15 which are insulated from the lamp by the fibre rings 16-17 and carry the outer terminals 18-19; the latter are connected by the wires 20-21 with the terminals 22-23 of a milli-ampere meter 24.

Fig. 3 shows the forms assumed by the flame according to the amount of fire-damp in the air, and also the corresponding graduated scale on the milli-ampere meter.

It should be noted that the voltage of the current from the thermo-electric couple is on the order of 1/20 volt, so that it will not produce a dangerous spark at the exterior; also, certain joints such as platinum and iridium-rhodium, iron and melchior metal, and silver-bismuth cannot be employed in this apparatus.

I claim:

1. In combination with a miner's lamp, of a circuit including an indicator of electromotive force and a nichrome thermo-couple supported on said lamp and terminating directly above the wick of said lamp and spaced therefrom.

2. In combination with a miner's lamp, of a nichrome thermo-couple supported on spaced contacts on said lamp, the free ends of said couple being soldered together and

terminating directly above the wick of said lamp and spaced therefrom, and a milliammeter connected with said thermo-couple.

3. In combination with a miner's lamp, of
5 a nichrome thermo-couple supported on
spaced contacts on said lamp, said couple
elements extending upwardly and being bent
over and down and soldered at their free
10 ends, said ends being positioned directly
above the wick of said lamp adapted to be
affected by the flame, conductor conduits ex-
tending from said contacts on said lamp
through the same and terminating on the
15 side thereof, insulated conductors connected
to said contacts and extending through said
conduits, and a milliammeter connected with
the free ends of said conductors.

In testimony whereof I affix my signature.

20

GEORGES SCHAULY.
